UNITED STATES PATENT OFFICE.

WILLIAM O. RUTLEDGE, OF GALVESTON, TEXAS.

CAR-UNCOUPLING DEVICE.

SPECIFICATION forming part of Letters Patent No. 394,301, dated December 11, 1888.

Application filed August 21, 1888. Serial No. 283,362. (No model.)

To all whom it may concern:

Be it known that I, WILLIAM O. RUTLEDGE, of Galveston, in the county of Galveston and State of Texas, have invented a new and Improved Apparatus for Uncoupling Cars, of which the following is a full, clear, and exact description.

This invention relates to devices for uncoupling railway-cars, and has for its object to provide an apparatus so constructed that the uncoupling may be quickly and readily effected from either the side or top of a car or from the locomotive.

The invention consists in an apparatus for uncoupling cars constructed and arranged as hereinafter described and claimed.

Reference is to be had to the accompanying drawings, forming a part of this specification, in which similar letters of reference indicate corresponding parts in all the figures.

Figure 1 is an end view of the body of a car with the invention applied thereto. Fig. 2 is a vertical section on the line *x* *x*, Fig. 1. Fig. 3 is a horizontal section, with parts broken away, on the line *y* *y*, Fig. 1; and Fig. 4 is a detail of the apparatus.

In the construction of this invention a U-shaped metallic strap, 1, is located on an ordinary draw-head, 2, and has a hole in line 30 with the coupling-pin hole of draw-head for the insertion of a coupling-pin, 3, the coupling-pin 3 resting on the strap 1. The latter is movable vertically on the draw-head, and is connected by a rod, 4, with the upper horizontal arm, 5, of a plate, 6, movable vertically in the casing 7, with folded edges 7', forming grooves and secured to the end of the car, the plate 6 having a lower horizontal arm, 8, resting upon a coiled spring, 9, located in a box 40 or casing, 10, on the end of the car at the lower end of edges 7'. The plate 6 is normally held up in the casing 7 by means of the spring 9, so that the coupling-pin 3 is held by strap 1 in position for coupling.

The coupling-pin may be coupled from either side of the car by means of levers 11, pivoted to the car and having their inner ends projecting over the upper arm, 5, of plate 6. Upon lifting up the outer end of one of the 50 levers 11 its inner end presses against the arm 5 and forces down the plate 6, compressing the coiled spring 9 beneath the arm 8, and by

means of rod 4 moving the strap 1 downward and carrying the pin 3 into coupled position. The plate 6 is held down against the tension 55 of spring 9 by means of a lip or projection, 12, on a horizontally-movable plate, 13, projecting through a slot, 14, in the wall of the car and a slot, 14', in the casing 7, and movable over the upper end of plate 6. The plate 13 60 is mounted on the upper end of a spring-strip, 15, secured to the inside of the car, and is formed with bent arms 16, which project through the slot 14 and bear against the inner ends of levers 17, pivoted to the end of the 65 car and extending out to the sides of the same. By pulling on the outer end of one of the levers 17 at either side of the car the inner end of the lever will press the adjacent arm 16 through the slot 14, thereby moving back 70 the plate 13 and releasing its lip 12 from the upper end of plate 6. The latter is then thrown up by spring 9, and thereby raises strap 1 and uncouples pin 3. The release of lip 12 from plate 6 and the uncoupling may 75 also be effected from the top of the car by a vertical lever, 18, pivoted to the end of the car and having one end bearing against one of the arms 16 and the other projecting above 80 the top of the car. The uncoupling may be also effected from the locomotive of a train by the engineer by means of a vertical lever, 19, pivoted to the end of the car and having one end bearing against one of the arms 16 and its other end pivotally connected to the end 85 of a horizontal lever, 20, pivoted beneath the car and having an operating rod or cord, 21, extending to the cab of the locomotive.

It will thus be seen that by means of this device an effective uncoupling apparatus is 90 provided which may be readily and quickly operated from either side of a car, from the top, or from the locomotive by the engineer.

In case of a car or several cars being uncoupled by the engineer, the brakes will be 95 automatically applied by the detachment of the brake-couplings.

Having thus described my invention, what I claim as new, and desire to secure by Letters Patent, is—

1. In an uncoupling apparatus for railway-cars, a draw-head provided with a vertically-movable coupling-pin support and lifting-frame, a spring holding the coupling-pin sup-

port in raised position, mechanism, substantially as described, for lowering the coupling-pin support, a catch for holding the pin-support in lowered position, and a mechanism, 5 substantially as described, for releasing the catch, substantially as shown and described.

2. In an uncoupling apparatus for railway-cars, a draw-head provided with a vertically-movable coupling-pin support and lifting-frame, a spring holding the coupling-pin support in raised position, a catch for holding the pin-support in lowered position, and a lever mechanism for releasing the catch and effecting the uncoupling of a car, substantially as 15 shown and described.

3. An uncoupling apparatus for railway-cars, consisting of a draw-head provided with a vertically-movable coupling-pin support and lifting-frame, a coiled spring holding the 20 pin-support and lifting-frame in raised position, a spring-actuated catch holding the pin-lifting frame in lowered position, levers for depressing the pin-lifting frame, pivoted to the end of the car and having one end located adjacent to the side of the car and the other projecting over the top of lifting-frame, levers for releasing the spring-catch, pivoted to the end of the car and having one end projecting at the side of the car and the other 25 end bearing against the spring-catch, a lever pivoted to the end of the car with one end projecting above the top of the car and the other end bearing against the spring-catch, and a lever pivoted to the end of the car with 30 one end bearing against the spring-catch and the other pivotally connected to the end of a 35

horizontal lever pivoted beneath the car and having a connection extending to the cab of a locomotive, substantially as shown and described.

4. An uncoupling apparatus for railway-cars, consisting of a draw-head, 2, the coupling-pin-supporting strap 1, vertically movable thereon, the vertically-movable plate 6, located in the casing 7 and having a horizontal arm, 8, at its lower end, resting upon a coiled spring, 9, in a casing, 10, and a horizontal arm, 5, at its upper end connected by a rod, 4, with the pin-supporting strap 1, the horizontal plate 13, with lip 12, and arms 16, 50 projecting into slot 14 in the wall of car and slot 14' in casing 7, and mounted on spring-arm 15, horizontal pivoted levers 11, having one end extending over arm 5 of plate 6 and the other located at the sides of the car, horizontal pivoted levers 17, having one end bearing against arms 16 and the other located at the sides of the car, a vertical pivoted lever, 18, having one end bearing against the plate 13 and the other end located at the top of the car, 55 and a vertical lever, 19, having one end bearing against the plate 13, and a horizontal lever, 20, having one end pivotally connected to lever 19 and the other end provided with a connecting-rod, 21, leading to the cab of the 60 locomotive, substantially as shown and described.
